Des. 228,577
Patented Oct. 9, 1973

228,577

LENS CLUSTER UNIT FOR PHOTOPRINTING

Richard M. Artz, 3902 Silverton Road NE.,
Salem, Oreg. 97308

Original design application May 28, 1970, Ser. No.
23,198, now Patent No. 223,593, dated May 9,
1972. Divided and this application June 28, 1971,
Ser. No. 157,811

Term of patent 14 years

Int. Cl. D16—03
U.S. Cl. D61—1 Q

FIG. 4

FIG. 2

FIG. 1

FIG. 3

FIG. 1 is a top plan view of a lens cluster unit for photoprinting showing my new design;

FIG. 2 is a side elevational view of FIG. 1 as taken from line 1—1;

FIG. 3 is a side elevational view of FIG. 1 as taken from line 2—2;

FIG. 4 is a bottom plan view thereof.

This application is a division of Ser. No. D. 23,198, filed May 28, 1970, now patent No. D. 223,593 on May 9, 1972.

I claim:

The ornamental design for a lens cluster unit for photoprinting, as shown and described.
